SAFETY GRIP BAR FOR A BATHROOM OR THE LIKE

William R. Brewer, Arleta, Calif., assignor to Hamilton C. de Jong (doing business as Safety Brothers), Pasadena, Calif.

Filed Dec. 26, 1967, Ser. No. 9,904

Term of patent 14 years

(Cl. D33—21)

FIG. 1 is a perspective view of a safety grip bar for bathroom or the like showing my new design;

FIG. 2 is a top plan view of the same;

FIG. 3 is a front elevational view of the same;

FIG. 4 is a bottom plan view of the same; and

FIG. 5 is a right side elevational view of the same.

I claim:

The ornamental design for a safety grip bar for a bathroom or the like, as shown.
